SHOE

Original Filed Nov. 17, 1920 2 Sheets-Sheet 2

Inventor:
Frank G. Delbon
By his Attorney,
Charles C. Gill.

UNITED STATES PATENT OFFICE.

FRANK G. DELBON, OF BROOKLYN, NEW YORK.

SHOE.

Application filed November 17, 1920, Serial No. 424,611. Renewed May 28, 1924.

To all whom it may concern:

Be it known that I, FRANK G. DELBON, a citizen of the United States, and a resident of Brooklyn, in the county of Kings and State of New York, have invented certain new and useful Improvements in Shoes, of which the following is a specification.

The invention relates to the inner-sole portion of shoes and boots, and it consists in the novel features and structure hereinafter described, and particularly pointed out in the claims.

One of the principal objects of the invention is to produce an inner sole of particular arch formation and capable, when in use, of maintaining its form and integrity even under the weight of a heavy person who may be wearing the shoes. Another purpose of the invention is to provide an inner-sole structure containing a metallic arch prop or support and of particular formation and with the prop so disposed and held that it will leave a smooth surface at the top of the inner sole and not interfere with the proper sewing and manufacture of the shoe in accordance with known mechanism and methods.

The invention will be fully understood from the detailed description hereinafter presented, reference being had to the accompanying drawings, in which:

Fig. 1 is a bottom view of an inner-sole constructed in accordance with and embodying the invention;

Fig. 2 is an edge view of the same, taken from the left hand side of Fig. 1;

Fig. 3 is a bottom view of the same, with the metallic arch prop or support and the lower covering layer or ply removed from the main body of the sole;

Fig. 4 is a vertical section through the sole of my invention, taken on the dotted line 4—4 of Fig. 1;

Fig. 5 is a transverse section through the same, taken on the dotted line 5—5 of Fig. 4, and

Fig. 6 is a detached top view of the metallic arch prop or support which I embed within the sole.

In the drawings, 10 designates the main body of the inner-sole or inner-sole proper, 11 the metallic arch prop or support, and 12 a lower layer or ply of leather which I se-

cure to the lower surface of the sole 10 and over the lower surface of the support 11, which becomes embedded within the sole of the shoe.

The inner-sole 10 will be of suitable edge outline and formed with such customary features, incident to the manufacture of a shoe, as may be required. A feature of the sole 10 having to do with my invention resides in the upwardly arched and curved side member 13 which is integral with the arch portion of the sole and curves upwardly therefrom to fit against the curvature at the inner side of a foot forwardly of the heel. The upwardly arched member 13 has a convexly curved upper edge and is of substantial dimensions so as to engage a large surface of the foot and afford a substantial support at the side of the arch portion of a foot. The sole 10 has formed in its lower surface, at the arch-portion thereof, a recess or socket 14 of a form and size to snugly receive the metallic arch prop or support 11, this recess starting inwardly from near the outer side edge of the sole 10 and extending upwardly along the curved member 13 of said sole to near the upper edge thereof.

The arch prop or support 11 is curved correspondingly with the member 13 of the sole and with those portions of the sole which merge into said member 13, as shown in Fig. 5, and said arch prop or support 11 is formed with punctures 15 whose flanges extend upwardly and are driven into the material of the sole 10 from the lower side thereof, as shown in Fig. 5, whereby said arch prop or support becomes anchored or secured to the sole 10 within the outline of the recess or seat 14 provided therefor.

The metallic arch prop or support 11 by extending from near the outer edge of the sole 10 in a direction toward the inner edge thereof and upwardly along the member 13 to approximately near the upper edge thereof, is enabled to maintain the integrity of the arch of the sole and of the initial formation of the member 13 and to effectually resist the weight of a heavy person who may wear the shoe.

It will be seen on reference to Fig. 6 that the arch support or plate 11 is of special configuration and that the curved upwardly extending side thereof has at its base a width equal to the full length of said support and

is of such a width as to be of sufficient strength to support the weight of a heavy person who may wear the shoe.

The metallic arch prop or support 11 is of such a width as to be of sufficient strength to support the weight of a heavy person who may wear the shoe.

The metallic arch prop or support 11 is of such a width as to be of sufficient strength to support the weight of a heavy person who may wear the shoe.

The metallic arch prop or support 11 is of such a width as to be of sufficient strength to support the weight of a heavy person who may wear the shoe.

that the upwardly extending curved portion of said plate or support 11 is of considerable area and extends upwardly to provide a support for the bottom and side of the arch portion of the human foot, said plate extending upwardly to a point enabling it to support the plantar arch of the foot particularly along the line of the tarsal bones, it being apparent that the proportions and location 5 of the supporting plate 11 are such as to take care of the plantar ligament of the foot and those bone portions at the joints between the heel bone and the scaphoid bones of the human foot, thereby distinguishing my invention from an ordinary longitudinal arch support having a little side wing appended 10 to it.

The arch prop or support 11 is covered over at its lower surface by the layer of 15 leather 12 which, as shown, extends from the usual sewing lip or ridge 16 adjacent to the outer side edge of the sole 10 toward the inner side edge of said sole and up along the arch member 13 of the sole, said covering 20 layer or ply 12 being secured near its outer side edge by sewing 17 to the sole 10. The covering layer 12 constitutes an extra ply for the arch member 13 of the sole and at its upper edge is secured thereto by a line 25 of sewing 19, and said layer 12 adds material stability to the inner sole of the shoe and when in its final position forms a portion thereof. The layer 12 helps to conceal 30 and support the arch prop 11 and affords a proper surface against which the shoe-upper and outer sole may be applied in accordance with customary methods of manufacture. The arch prop 11 does not extend to 35 the extreme outer side edge of the sole 10, but is set inwardly therefrom, as indicated in Figs. 1 and 3, so as not to interfere with the proper application of the upper and outer sole during the manufacture of the shoe.

40 The layer 12 is slit or undercut, as at the line 20, to form a projecting lip 21 to which the upper of the shoe may be sewed, thus permitting the proper association of the other parts of the shoe with the inner-sole 45 without the stitches passing through the arch prop or plate 11, the lip 21 coinciding with or constituting an extension of the usual ridge or lip 16 where it extends along the inner side edge of the sole, as shown in Fig. 50 1. I provide the lip 21 so as to make it possible to carry on the proper manufacture of the shoe and at the same time have the metallic arch prop or support 11 extend along the undersurface of the sole 10 and 55 up along the side member 13. It will be seen on reference to Fig. 5 that the lip 21 may be utilized as an edge for the sewing operation without interference with or from the plate 11. The usual slit or undercut 60 22 provides the lip or ridge 16 at the outer

side edge of the sole 10 and this undercut receives, by preference, the adjacent edge of the layer 12, as indicated in Fig. 5.

The upper surface of the sole 10 is undercut along the line 23 (Fig. 5) to receive the 70 line of sewing 17 by which the outer or left hand edge of the covering layer 12 is secured to the sole 10, the undercut 23 permitting me to secure the layer 12 in position without creating a ridge, due to the sewing, on the 75 upper surface of the sole 10. I also form an undercut 24 in the upper surface of the upper portion of the side arch-member 13 to admit of the sewing 19 for securing the upper edge of the layer 12 in position without 80 creating a ridge on the inner surface of said member 13.

My invention thus comprises the construction hereinbefore described involving 85 the inner sole 10, inner side arch-member 13, metallic arch prop or support 11 and lower layer 12 concealing the arch prop 11 and serving as an extra ply along the arch of the sole and said member 13, provision being 90 made for preventing the formation of 95 ridges at the upper surface of the sole and said member 13 and for the proper sewing of the upper or other portions of the shoe to the inner-sole without interference from or by reason of the presence of the metallic 100 arch prop or support 11.

My invention has been designed with the view of producing a shoe which will adequately and properly support the arch of the foot and resist the severe strains which 105 come upon the arch portion of a shoe when the shoe is worn by a heavy person.

What I claim as my invention and desire to secure by Letters-Patent, is—

1. An inner sole for a shoe, comprising 105 a main stiff leather body having an arch portion and thereat and integrally therewith a laterally and upwardly curving side member of substantial proportions to engage the inner side of the arch portion of a 110 foot, a lower leather layer extending over the bottom of the arch of the sole and upwardly over and conforming to the outer surface of said side member, and a metallic arch support between said sole and lower 115 layer and extending across said arch portion of the sole and upwardly along said side member and conforming to the curvature of said parts, said main body having formed therein a recess conforming to the 120 dimensions of said metallic arch support and receiving the same, and said lower layer being secured by sewing along its lower outer side edge to said sole inwardly from the sewing ridge adjacent to the outer side 125 edge thereof and by sewing along its upper edge to the upper edge portion of said side member upwardly beyond the upper edge of said metallic arch support.

2. An inner sole structure as claimed in 130

claim 1, in which said main body is undercut in its upper surface to receive the two lines of sewing securing said lower layer in position, the sewing thus being concealed at the upper surface of the inner sole.

3. An inner sole structure as claimed in claim 1, in which said lower layer is under-

cut to form a lip constituting an extension of the lip extending along the bottom of the inner sole to receive the upper.

Signed at New York city, in the county of New York and State of New York, this 15th day of November, A. D. 1920.

FRANK G. DELBON.
